FRED S. CARR

Attornies

UNITED STATES PATENT OFFICE.

FRED S. CARR, OF BROOKLINE, MASSACHUSETTS, ASSIGNOR TO CARR FASTENER COMPANY, OF CAMBRIDGE, MASSACHUSETTS, A CORPORATION OF MAINE.

TURN-BUTTON FASTENER.

1,223,146.

Specification of Letters Patent. Patented Apr. 17, 1917.

Application filed October 23, 1916. Serial No. 127,058.

To all whom it may concern:

Be it known that I, FRED S. CARR, a citizen of the United States, residing at Brookline, in the county of Norfolk and 5 State of Massachusetts, have invented new and useful Improvements in Turn-Button Fasteners, of which the following is a specification.

This invention relates to a fastener for 10 carriage curtains and the like, comprising a shank or stud adapted to be attached to a support such as the body of a vehicle or a member of the frame of a vehicle top, and formed to enter a buttonhole or eyelet in a 15 curtain or cover portion, and an oblong button pivoted to the shank and formed to register with and freely enter a buttonhole when turned to one position and to be turned crosswise of the buttonhole to overhang portions 20 of the margin thereof and confine the curtain or cover portion against removal from the shank. The shank is usually of oblong form corresponding to that of the buttonhole and button.

25 Fasteners of this character, known as turn-button fasteners, are provided with means for yieldingly confining the button either in registration with the shank or crosswise thereof, so that the button will remain in either position until forcibly turned therefrom.

The invention has for its chief object to enable the button to be yieldingly confined in either of the described positions without 35 the employment of retaining devices supplemental to the shank and button and formed separately therefrom, the invention, in its preferred form, being embodied in only two parts or pieces which include the 40 means for yieldingly confining the button in its different positions.

Another object of the invention is to provide a turn-button fastener constructed entirely of sheet metal and therefore of minimum weight and cost.

45 The invention consists in the improvements which I will now proceed to describe and claim.

Of the accompanying drawings forming 50 a part of this specification,—

Figure 1 represents a side view of a turn-button fastener embodying my invention;

Fig. 2 represents an end view of the same;

Fig. 3 represents a top view;

Fig. 4 represents a side view of the shank 55 portion with a different form of attaching base;

Fig. 5 represents a plan view of the shank portion shown by Fig. 4;

Figs. 6 and 7 represent respectively a side 60 and an end view of the button, and illustrate a modification hereinafter described;

Fig. 8 represents an enlarged section on line 8—8 of Fig. 1;

Fig. 9 represents an enlarged section on 65 line 9—9 of Fig. 2;

Fig. 10 represents a section on line 10—10 of Fig. 8;

Fig. 11 represents a view similar to Fig. 10, showing the button turned crosswise of 70 the shank;

Fig. 12 represents a plan view of the blank from which the button is made;

Fig. 13 represents a section on line 13—13 of Fig. 12;

Fig. 14 represents a view similar to Fig. 1, showing a modification;

Fig. 15 represents a view similar to a portion of Fig. 8, illustrating a modification.

Figs. 16, 17 and 18 are sectional views 80 illustrating a modification.

Fig. 19 represents a view similar to a portion of Fig. 8 showing a modification.

The same reference characters indicate the same or similar parts in all the views. 85

In the drawings, 16 represents the shank and 17 the button of a turn-button fastener. In the embodiment of the invention here shown the shank is a hollow post formed from sheet metal by suitable dies, of oblong 90 form in cross section and provided at its inner end with an attaching base 18 adapted to be secured to a support in any suitable way. For example, the base may be provided with integral prongs 19 adapted to penetrate and be clenched upon the part or member that carries the shank. Figs. 4 and 5 show an attaching base which is elongated and provided with orifices 20 adapted to receive attaching screws.

100 The outer end of the shank is practically closed to provide a flat face, which is provided with frictional button-engaging means to yieldingly confine the button in different positions, said means being embodied in a 105 hollow polygonal projection 21 integral with the shank and provided with a plurality of outwardly facing sides 22.

The button 17 is a flexible inverted cup made of sheet metal and having an open mouth which receives the projection 21, the button being oblong in cross section and 5 formed to register with the shank to enter a buttonhole therewith, and to stand crosswise of the shank, as indicated by dotted lines in Figs. 2 and 8, to overhang the longer sides of the shank and portions of the margin of 10 a buttonhole on the shank.

The margin of the button shown by Figs. 2, 3, 9, 10, 11 and 14 is provided with slots 24 preferably formed in the ends of the button, as shown by Figs. 2 and 3, although 15 said slots may be formed in the sides of the button, as shown by Fig. 14. The slots subdivide the margin of the button into resilient portions or jaws the inwardly facing sides of which are adapted to yieldingly 20 engage opposite sides 22, of the polygonal projection, as indicated by Figs. 10 and 11, and thus yieldingly confine the button in either of the two positions described, the yielding or resilient portions of the button 25 being adapted to spring inwardly against the faces 22 and have elongated contact therewith, so that considerable force is required to turn the button from either position to the other.

30 The button is therefore provided with a resilient inwardly facing expansible margin or marginal portion adapted to frictionally engage fixed outwardly facing sides of the polygonal projection on the shank 16. The 35 elongated contact between said marginal portion and fixed sides prevents liability of accidental rotation of the button.

A pivotal connection is provided between the button and the shank, said connection 40 preferably including a hollow stud 25 which is integral with the button and projects from the crown portion thereof into the interior of the button. Said stud is provided with a reduced inner end portion 26 and with an 45 annular shoulder 27 between the portion 26 and the body of the stud. The projection 21 is provided with a circular aperture 28 constituting a bearing in which the stud portion 26 is journaled, said portion being inserted in the orifice 28 and upset on the under side of the projection 21, as shown by 50 Figs. 8 and 9. The projection 21 therefore constitutes a bearing and a seat for the stud 25, the shoulder 27 being seated on one side 55 of said projection, and the upset portion 26 being seated on the opposite side.

The button may be formed from a blank 17^a, said blank being flat and provided with the stud 25, as indicated by Figs. 12 and 13. 60 The blank is provided with curved edges 17^b which form the sides of the slots 24 when the blank is bent by the action of suitable dies to form the hollow cupped button.

It will now be seen that the described fastener may be made of only two pieces or

parts, and that said parts have provision for suitably connecting the button and shank and for yieldingly confining the button in different positions relatively to the shank.

I do not limit myself to a pivot stud integral with the button. As shown by Fig. 15, a tubular stud 25^a may be employed, said stud having a head 25^b seated on the margin of an orifice in the crown of the button, the inner end of the stud being inserted in the 75 aperture of the projection 21 and upset on the under side of said projection.

The slots 24 may be omitted, the margin of the cupped button being continuous as shown by Figs. 16, 17 and 18. In this case, 80 the flexibility of the button margin enables it to closely hug the projection 21 when the button is in either of the positions shown by Figs. 16 and 18, and to bulge outwardly when in the intermediate position shown by 85 Fig. 17.

As shown by Fig. 19, a tubular stud 25^a may be formed integral with the projection 21 on the shank 16, the outer end of the stud being extended through an orifice formed in 90 the crown of the button 17 and upset to secure the button to the stud.

The polygonal projection 21 having outwardly facing sides, is adapted to coöperate as described, with a cupped button, the 95 external surface of which is flush with the external surface of the shank when the button registers with the stud to permit the application of a curtain eyelet, so that the eyelet may be easily moved to place on the 100 shank.

As implied in the foregoing description and in the following claims, I am not limited to the specific construction of the preferred embodiment of my improvement 105 shown by the drawing, except as otherwise required in certain of the more limited claims.

Having described my invention, I claim:

1. A turn-button fastener comprising a 110 shank formed to enter a buttonhole and having an attaching base at its inner end, and a fixed polygonal projection at its outer end, the sides of which face outwardly, and a button composed of an oblong flexible inverted cup pivoted to the shank, the mouth of said cup receiving said projection and having resilient inwardly facing side portions adapted to yieldingly engage and have elongated contact with opposite sides of said 115 projection to yieldingly confine the button in different positions relatively to the shank.

2. A turn-button fastener comprising a shank formed to enter a buttonhole and having an attaching base at its inner end, 125 and a fixed polygonal projection at its outer end, the sides of which face outwardly, and an oblong cupped sheet metal button pivoted to the shank and having slots subdividing its margin into resilient inwardly facing 130

portions adapted to yieldingly engage and have elongated contact with opposite sides of said projection to yieldingly confine the button in different positions relatively to 5 the shank.

3. A turn-button fastener comprising a shank formed to enter a buttonhole and having an attaching base at its inner end, and a fixed polygonal projection at its outer 10 end, the sides of which face outwardly, an oblong button having resilient inwardly facing portions adapted to yieldingly engage and have elongated contact with opposite sides of said projection, and a pivotal 15 connection between said shank and button.

4. A turn-button fastener comprising a hollow sheet metal shank formed to enter a buttonhole and having an attaching base at its inner end, and a hollow polygonal 20 projection at its outer end, the sides of which face outwardly, and an oblong button pivoted to the shank and having resilient inwardly facing portions adapted to yieldingly engage and have elongated contact 25 with two of said sides to yieldingly confine the button in different positions relatively to the shank.

5. A turn-button fastener comprising a hollow sheet metal shank formed to enter 30 a buttonhole and having an attaching base at its inner end, and a hollow polygonal projection at its outer end, the sides of which face outwardly, said projection being provided with a central bearing, an oblong 35 cupped sheet metal button having resilient inwardly facing portions adapted to yieldingly engage and have elongated contact with said sides, and a stud engaged with said button and rotatable in said bearing to 40 pivotally connect the button with the shank.

6. A two-piece turn-button fastener comprising a hollow sheet metal shank formed

to enter a buttonhole and having an attaching base at its inner end, and a hollow polygonal projection at its outer end, the 45 sides of which face outwardly, said projection being provided with a central bearing, an oblong cupped sheet metal button having resilient inwardly facing portions adapted to yieldingly engage and have elongated 50 contact with said sides, and a hollow sheet metal stud integral with the button and rotatable in said bearing to pivotally connect the button with the shank.

7. A turn-button fastener comprising a 55 sheet metal hollow button having a resilient margin and an internal hollow pivot stud integral with the button and provided with an annular shoulder near its inner end, and a sheet metal hollow shank having an apertured hollow polygonal projection at its outer end, the sides of which face outwardly and frictionally engage said margin, said projection having an orifice constituting a bearing for said stud and an outer face constituting a seat for the said shoulder, the inner end of said stud being upset upon the under side of said projection. 65

8. A two-piece turn-button fastener comprising a hollow sheet metal shank formed 70 to enter the buttonhole, and having a fixed polygonal projection at its outer end, the sides of which face outwardly, and an oblong cupped sheet metal button having resilient inwardly facing portions adapted to 75 yieldingly engage and have elongated contact with two of said faces, and a hollow sheet metal stud integral with one of said pieces and having a bearing in the other piece to pivotally connect the button with 80 the shank.

In testimony whereof I have affixed my signature.

FRED S. CARR.
